UNITED STATES PATENT OFFICE.

ERNEST C. SCHRAEDER, OF MORGANTOWN, WEST VIRGINIA, ASSIGNOR TO ECONOMY
GLASS COMPANY, OF MORGANTOWN, WEST VIRGINIA, A CORPORATION OF WEST
VIRGINIA.

DESIGN FOR A GOBLET OR SIMILAR ARTICLE.

Application filed January 31, 1927. Serial No. 20,553. Term of patent 3½ years.

To all whom it may concern:

Be it known that I, ERNEST C. SCHRAEDER, a citizen of the United States, residing at Morgantown, in the county of Monongalia and State of West Virginia, has invented a new, original, and ornamental Design for a Goblet or Similar Article, of which the following is a specification, reference being had to the accompanying drawing, forming a part thereof.

Figure 1 illustrates a side elevation of a goblet showing my new design, the lining

representing shade lines illustrating shading produced by the waves produced in the glass, and

Figure 2 is a vertical sectional view taken along the line 2—2 of Figure 1.

The dominant feature of the invention consists in the ornamentation shown.

I claim:

The ornamental design for a goblet, or similar article as shown and described.

ERNEST C. SCHRAEDER.
